UNITED STATES PATENT OFFICE.

HOWARD J. OTIS, OF KANSAS CITY, MISSOURI.

WRENCH.

Application filed June 12, 1925. Serial No. 36,618.

This invention relates to improvements in wrenches of the type usually referred to as "monkey wrenches".

It is the object of this invention to produce a wrench which shall be so constructed that it can readily be converted into a hammer and which shall also be adapted to be employed as a tire iron for removing and replacing tire casings on automobile wheels. In addition, this wrench is also provided with claws for pulling nails, bolts or rivets.

My invention can be most clearly described and will be most readily understood when reference is had to the accompanying drawing in which the preferred embodiment thereof is shown and in which:

Fig. 1 is a plan view of my improved wrench showing the same in adjusted position;

Fig. 2 is a section taken on line 2--2, Fig. 1;

Fig. 3 is a section taken on line 3--3, Fig. 1, and shows the parts in locked position;

Fig. 4 is a section similar to Fig. 3, but shows the parts in unlocked position;

Fig. 5 is a transverse section taken on line 5--5, Fig. 1, and

Fig. 6 is a section similar to the section shown in Fig. 3 and shows a slight modification.

My improved wrench comprises a handle portion 1 of metal to one end of which is secured the head or stationary jaw member 2. The handle and head are so connected that they are practically integral. This is accomplished by welding or brazing. The head 2 has one end 3 flat in the manner usual in wrenches of this type. The other end 4 is somewhat larger and flatter so as to be suitable for use as a hammer. It is also provided with spaced claws 5 that may be employed for pulling nails, removing bolts or for any similar use and they may also be used in removing tires. The handle has a channel 6 on one side. A portion of the bottom surface of this channel is provided with a number of transverse teeth 7. Slidably secured to the handle is a movable jaw member 8. This jaw member has a rectangular opening through which the handle 1 is inserted. An opening 9 extends through one side of the movable jaw and through this opening the handle portion 10 of the detent member projects. This detent has an arm 11 that extends substantially at right

angles to the handle 10. Two teeth 12 are provided near the corner formed by the two arms 10 and 11. These teeth are adapted to engage in the spaces between the teeth 7 in the manner shown in Figs. 3 and 6. The adjacent surfaces of the arms 10 and 11 are connected by an inclined surface 13 whose ends lie in a plane extending at an angle to the central portion of said surface and at right angles to the surfaces of arms 10 and 11 so as to form notches 14 and 15. When the parts are in locked position (Figs. 3 and 6) the notch 14 is engaged by the square corner 16 and the forward end of arm 11 contacts with the inner surface of the opening in the head 8. When the parts are in locked position, it is evident that there can be no movement of the movable jaw member 8 on the handle 1 in one direction. When the parts are to be unlocked, it is necessary to move the movable jaw member 8 on the handle towards the stationary jaw until the corner 16 disengages the notch 14. By a pressure of the finger on the end of arm 10, the locking member can then be moved into the position shown in Fig. 4 in which position the movable jaw member 8 can be moved in either direction.

It is obvious from an inspection of Figs. 3, 4 and 6 that the jaw 8 must be moved a short distance towards the right (Fig. 3) before it can be unlocked or before the detent can be released (Fig. 4). If the wrench is so adjusted that the jaws fit snugly to the sides of a nut, the wrench must be removed before the jaw member 8 can be adjusted which is no objection as no adjustments are necessary when the jaws have a snug fit with the nut. When the wrench is to be adjusted so as to fit nuts of various sizes, the adjustments are preferably made before the wrench is applied to the nuts.

In Fig. 6 I have shown a slightly modified form in which the arm 10 is provided with an elongated slot 17 which receives the end 18 of the screw 19. The object of this construction is to hold the locking member in place and prevent it from getting lost when the movable jaw member 8 is removed from the handle as it is supposed to be when the tool is employed as a hammer or a tire iron.

It will be noticed that the end 20 of the handle is tapered and slightly curved so that it can be used in removing and applying

tire casings to automobile wheels. Since the movable jaw 8 is held in place by means that can be readily released and can therefore be readily removed from the handle, 5 it is evident that the tool may be employed as a hammer or tire iron by simply removing the movable jaw member 8. The fact that the handle has a channel 6 on one side and that the teeth 7 are in the bottom of 10 this channel gives the handle a smooth outer surface in contact with the hand of the operator, which is a marked improvement over constructions in which the teeth are on the outer surface of the handle.

15 I wish to call particular attention to the locking means employed by me as its great simplicity permits the wrench to be constructed at the minimum expense and with the minimum amount of labor.

20 Having now described my invention what I claim as new is:

1. A wrench comprising, in combination, a handle having a transversely extending jaw member rigidly secured to one end 25 thereof, said handle having a substantially rectangular cross section and provided with a longitudinally extending channel along one side, a portion of the bottom surface of 30 said channel being provided with teeth, a movable jaw member adapted to be slidably connected to the handle, said movable jaw member having a rectangular opening for the reception of the handle, said movable jaw member having a second opening which

extends through one side thereof, and a 35 pawl member operatively associated with said movable jaw member and loosely mounted therein, said pawl member being of bell crank shape, one end being adapted to lie within the rectangular opening and 40 the other to extend through the opening in the side, said pawl member having a projecting lug near its apex, said lug being adapted to engage the teeth in the bottom of the channel. 45

2. A wrench comprising, in combination, a handle, a jaw member permanently and nonremovably secured to one end thereof, said handle having a substantially rectangular cross section and a plurality of transverse 50 notches on one side, a movable jaw member having an opening adapted to receive said handle and another opening in the side, a bell crank shaped detent carried by said movable jaw member and loosely mounted 55 therein said detent having two arms extending substantially at right angles to each other, one of said arms projecting through the opening in the side of the movable jaw member, the other lying within the first 60 mentioned opening in the movable jaw member, said detent having an outwardly extending projection for engaging the transverse notches so as to prevent movement of the movable jaw member in one direction. 65

In testimony whereof I affix my signature.

HOWARD J. OTIS.
